UNITED STATES PATENT OFFICE.

GEORGE E. GANNON, OF COLORADO CITY, COLORADO

VALVE FOR CORROSIVE LIQUIDS.

No. 823,493.

Specification of Letters Patent.

Patented June 12, 1906.

Application filed May 20, 1905. Serial No. 261,399.

To all whom it may concern:

Be it known that I, GEORGE E. GANNON, a citizen of the United States, residing at Colorado City, in the county of El Paso and State of Colorado, have invented certain new and useful Improvements in Valves for Corrosive Liquids, of which the following is a specification.

My invention relates to valve devices for use with liquids which would corrode the hard metals usually employed and in which therefore a soft and non-corrosive metal is desirable; and my invention consists in constructing the valve device so as to secure the advantages of a soft non-corrosive material, while preventing it from becoming inefficient from mechanical pressure, as fully set forth hereinafter and as illustrated in the accompanying drawings, in which—

Figure 1 is a sectional elevation showing one form of valve device embodying my improvement especially adapted to be built up from separate pieces. Fig. 2 is a plan view of Fig. 1.

The casing A of the valve device may be of any suitable construction which affords a port or neck 3 for connection with the inlet or supply, an outlet port or neck 4, a valve-seat, and a neck 1 opposite the valve-seat for the support of the cap C, through which extends the valve-stem.

In the construction shown the valve is shown as made of tubing of soft metal, the different sections burned or soldered together, the necks 3 and 4 being soldered to the short tube constituting the neck 1 and the neck 3, communicating with the end of the tube 1 through a curved tube 5, communicating at one end with the neck 3 and centrally with a short tube 2, extending to the lower end of the tube 1. The tube 5 also extends to and braces the neck or tube 4 and is soldered thereto, but does not communicate therewith. The tube 3 extends and is soldered to the tube 1, but does not communicate directly therewith, while the tube 4 communicates with the tube 1, as shown.

The seat α for the valve is formed within the casing below the necks 3 and 4, and, as shown, is at the upper end of the tube 2, where it is inclosed within the lower end of the tube 1, the latter projecting downward below the necks 3 and 4, so that the seat may be formed within this projecting portion.

Inasmuch as these parts are of metal which is of a character to resist corrosive liquids,

such as acids, and as such metals as can practically be employed are so soft that they would not of themselves support the mechanical pressure required in a valve device, I reinforce such portions of the soft-metal structure as are subjected to pressure. Thus the projecting end of the tube 1 is surrounded by a disk or ring 10, of hard metal, conforming to the exterior of the said tube adjacent to the seat α and suitably held in place, so as to prevent the expansion of the said seat under the pressure of the valve.

In the construction shown in Fig. 1 the end of each soft-metal neck is bent outward to form a flange a , and a ring of hard metal surrounds the neck bearing against the inside of said flange and is adapted to be connected to any other object in such a way as to clamp the flange and secure a tight joint with said object. In the case of the necks 3 and 4 the flange a would be clamped to the flange of the inlet or outlet pipe. The flange of the neck 1, however, is clamped to the cap C, provided with a suitable stuffing-box b , through which extends the stem E of the valve F. The stem of the valve is threaded and adapted to the socket of a yoke G, the base-piece of which incloses the packing-box of the cap, having a socket to receive the latter, and thereby strengthening the same to resist the pressure of the gland 13, and said base bears upon the cap, the latter and the flange a of the tube 1 being clamped between the said base and a surrounding ring 9. The clamping means shown consists of screw-bolts 11, having heads below the ring 10, nuts bearing on the under side of the ring 9 and other nuts bearing upon the base of the yoke G. By this construction the corrosive liquid is confined within a casing of non-corrosive material, and the latter is strengthened at all points necessary to resist mechanical pressure, which otherwise, owing to the soft nature of the material, would distort it and render it inefficient.

So much of the valve and its operating appliances as may be exposed within the casing must be protected from the action of the liquid, and I therefore envelop the valve and its stem 7 with an envelop 6 of soft non-corrosive metal, extending this envelop along the valve-stem 7 to a point above that which is inclosed by the stuffing-box when the valve is upon its seat.

Without limiting myself to the precise con-

struction and arrangement of parts shown, I claim—

1. A soft-metal valve device having a casing of soft metal consisting of a straight tube, 5 a curved tube connected at the ends to said straight tube and communicating with the latter at one end, a connecting-tube containing a valve-seat and a valve and operating devices therefor, and reinforcing-rings of hard metal around said connecting-tube, and around the ends of the straight tube.

2. The combination in a soft-metal valve device of a casing of soft metal, having necks 3 and 4, a tube 1 extending above and below said necks, a curved section 5, and a connection consisting of a tube 2, extending from the section 5 into the lower end of the tube 1 and formed into a valve-seat, a valve adapted to said seat and operating devices therefor, and reinforcing-rings around the necks 3, 4, and around the upper and lower ends of the tube 1.

3. The combination in a soft-metal valve device of a casing of soft metal, having necks 25 3 and 4, a tube 1 extending above and below said necks, a curved section 5, and a connec-

tion consisting of a tube 2, extending from the section 5 into the lower end of the tube 1 and formed into a valve-seat, a valve adapted to said seat and operating devices therefor, and reinforcing-rings around the necks 30 3, 4 and around the upper and lower ends of the tube 1, and bolts connecting the rings around the tube 1.

4. The combination with the soft-metal 35 casing, of a soft-metal cap having a stuffing-box, and a hard-metal reinforce inclosing said stuffing-box, substantially as set forth.

5. The combination of the casing A, soft-metal cap C having a stuffing-box, and a 40 yoke G adapted to support the valve and having a base-piece recessed to receive and reinforce the stuffing-box, substantially as set forth.

In testimony whereof I have signed my 45 name to this specification in the presence of two subscribing witnesses.

GEORGE E. GANNON.
